REFRIGERATOR CAR

Charles D. Bonsall, Pittsburgh, Pa., assignor to
Standard Railway Devices Company, a corpora-
tion of Delaware

Application June 9, 1939, Serial No. 278,276

10 Claims. (Cl. 105—404)

This invention relates to refrigerator cars used to transport perishable commodities at a predetermined temperature. The essential features of a refrigerator car are an insulated body to prevent or retard ingress of heat during warm weather and egress of heat during cold weather and a cooling or heating means depending upon the prevailing outside temperature.

This invention applies particularly to cars in which the cooling means, preferably containers for water ice, eutectic ice, brine or dry ice, are positioned immediately below the ceiling of the car. The lading is supported in spaced relation to the floor by a foraminous rack. Flues, preferably associated with the side walls of the car, communicate between the refrigerant compartment and the space under the floor rack to provide a path for the circulation of air. The path is from the refrigerant compartment downwardly through the aforementioned flues, through the space under the floor rack, and upwardly through the lading compartment to the refrigerant compartment.

It is an object of the invention to eliminate unnecessary weight from the structure of the car by adapting the refrigerant containers to function as side plates or upper chords of the side walls of the car. A further object of the invention is to adapt the containers to also function as carlines. Sideplates are commonly longitudinally extending frame members at the upper edges of the sidewalls and carlines are usually transversely extending members used to support the roof, refrigerant containers, or other structure disposed near the top of the car.

Another object of the invention is to securely brace the refrigerant containers against longitudinal movement thereof. The amount of ice carried in the containers may be as much as several tons and the inertia thereof during service movements of the car requires that the refrigerant containers be securely attached to the car structure.

It is another object of the invention to brace each container against the container adjacent thereto so that the thrusts thereon which occur due to the mass of the refrigerant and violent movements of the car are transferred to the end of the car. The ends of railway cars are commonly made of corrugated steel plate, which plate is well adapted to resist the thrust of a large mass of refrigerant. A further object is to provide spaces between the tanks for air circulation, thereby increasing the efficiency of the refrigeration.

Another object is to provide a structure in which the refrigerant containers function as the compression chord of a truss or girder, which truss or girder is comprised of substantially the entire car. The underframe of a car is usually strong and well adapted to function as the tension chord. By bracing the tanks against each other lengthwise of the car, a very strong structure is formed when used as a compression member. Various members of the side and end walls serve as the struts or web.

Another object of the invention is to increase the refrigerant capacity or reduce the necessary car height while retaining the same capacity. I accomplish this by positioning a portion of each container between vertical frame members, thereby using space heretofore wasted. This arrangement provides a secure attachment for each tank to the frame members and consequently to the adjacent tank.

Other objects and advantages of my invention will be apparent from the following detailed description by referring to the accompanying drawings.

25 In the drawings:

Fig. 1 is a transverse section of a refrigerator car embodying my invention.

Fig. 2 is a plan section of the car taken on line 2—2 of Fig. 1.

30 Fig. 3 is an enlarged view of a portion of Fig. 2.

Fig. 4 is a view similar to Fig. 3 showing a modified construction.

35 Fig. 5 is a transverse section showing a modified form of my invention taken on line 5—5 of Fig. 6.

Fig. 6 is a plan section taken on line 6—6 of Fig. 5.

40 Fig. 7 is an enlarged view of a portion of Fig. 6. The refrigerator car shown in the drawings embodies insulated walls 2, roof 3, and floor 4. The floor 4 is preferably supported by a plurality of spaced apart transversely extending beams 6 which are secured at the ends thereof to the outer

45 side sills 7. Each wall 2 preferably comprises outer posts 9 and outer sheathing 10 secured at the lower parts thereof to the outer side sill 7 and at the upper parts thereof to the outer side plate 12. The wall 2 also includes inner posts 50 15 and inner sheets 16 which are secured to the inner side sill 17, the sill 17 being secured to and insulated from the floor beams 6. The sheets 16 are formed with panels 19 projecting away from the interior of the car, which panels 19 are positioned between the inner posts 15. A lining 20

is provided to form the flues 21 between the panels 19 and lining 20.

In the modification shown in Figs. 1 to 3, the refrigerant containers 25 extend between the side walls 2 and are formed preferably of sheet metal reinforced with angles as will be herein-after described. Each container 25 preferably has vertically disposed angles 27 welded or otherwise secured to the corners thereof. Longitudinally extending angles 28 are secured to the lower corners of the container, said angles 28 extending between the vertical angles 27 and preferably being secured thereto. Transversely extending angles 30 are secured to the lower transverse edges of the container 25 and offset outwardly and downwardly at the ends thereof to overlap the angles 27 and 28, the overlapping ends preferably being secured together.

The vertical corner angles 27 are secured preferably by the rivets 35 to the inner posts 15 adjacent the ends of the containers 25 and the posts 15 intermediate the ends of the containers 25 are secured to the longitudinally extending angles 28. The containers 25 thus connect the upper ends of the posts 15 to form the upper chord or side plate of the inner wall structure. The containers 25 also join the opposite walls 2 of the car, thereby functioning as carlines. The tops 36 of the containers 25 may be used to support the roof insulation 37.

A drip pan or partition 40 is spaced below the container 25 to provide a space 41 therebetween and also spaced from one of the walls 2 to form an air inlet opening 42. Air in the space 41, being cooled by contact with the cold bottom 44 of the container 25, falls by reason of its greater density through the flue 21 to the space 46 under the floor rack 47 from where it permeates upwardly to the lading compartment 48. Upon being warmed by contact with the lading, the air flows through the opening 42 to the space 41 and the cycle is repeated.

In the modification shown in Fig. 4, the longitudinally extending angles 55 project beyond the end walls of the containers 25. The ends of the angles 55 of adjacent containers are in contact and are secured to the inner posts 15. The inertia thrust of the refrigerant is carried partly through the rivets 56 to the inner posts 15 and partly through adjacent containers to the end of the car. As clearly shown in Fig. 3, the projecting legs 57 of the angles 27 are in contact for the purpose of transferring thrusts to the end of the car. It is to be understood that the construction of a structure as shown may be difficult because of the accurate manufacturing required. It is intended, however, that substantially the same result could be obtained by inserting shims between certain members of adjacent containers to provide the contact between the containers which I claim as a part of my invention.

In the modification shown in Figs. 5 to 7, there is a row of refrigerant containers 65 positioned adjacent each side wall 2 and spaced apart at the center to form the duct 66. Air from the lading compartment 48 flows upwardly through the duct 66 to the spaces 67 below the containers 65 in which spaces it is cooled. It then flows through the flues 21 and space 46 as has been heretofore described. The inner sides 69 of the containers 65 are preferably suspended from the roof structure 3 by means of the inverted U shaped member 68.

The inner posts 15 preferably comprise a web

10, spaced apart flanges 71 provided with re-flanges 72. The containers 65 are positioned so that the corners 14 thereof nest in the pockets formed by the flanges 71 and re-flanges 72 of the posts 15. The containers 65 may be secured to the posts 15 by any convenient means. The sheets 76 have panels 77 pressed therein as has been heretofore described. The sheets 76 are preferably secured to the lower part of the container 65, such as by lapping the portions 79 associated with the panels 77 and butting the angular portions 80. The portions 81 between the containers may be secured to the posts 15 to form a water-tight seal so that condensation from the containers 65 or other moisture flows downwardly through the flues 21 and not into the insulation.

It will be readily seen that the structures herein shown and described are well adapted to transfer thrusts from one container to the adjacent container and finally to the end wall of the car. This arrangement is due partly to the necessity of providing a structure sufficiently strong to resist the inertia thrusts of the refrigerant. Another object of the arrangement is as follows:

The load in a railway car rests upon the floor. Cars are commonly designed so that the floor, which includes the underframe of the car, carries 30 the major portion of the load. The remainder of the load is carried by the two side walls of the car functioning as girders or trusses, according to the type of side. I claim as an improvement in refrigerator cars the bracing of overhead refrigerant containers against each other to enable them to cooperate to resist compression loads and thereby function as the compression chord of a truss or girder in which the floor structure is the tension chord and the side and end walls comprise the struts or web. The fact that a railway car has considerable height provides a relatively large distance between the tension and compression chords, thereby forming a strong and light truss or girder.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having spaced apart side walls and a roof, a refrigerant container 55 below the roof and extending between said walls to form a roof supporting carline, said walls having load supporting posts disposed adjacent the interior of the car, the upper ends of said posts being secured to said container so that said container forms upper chords of said wall.

2. In a refrigerator car having spaced apart side walls and a roof, a row of refrigerant containers 65 below the roof and adjacent one of said walls, said wall having load supporting posts disposed adjacent the interior of the car, the ends of said containers being secured to the upper ends of said posts with the adjacent ends of adjacent containers being secured to a common post so that said containers form an upper chord of said wall.

3. In a refrigerator car having spaced apart side walls and a roof, a row of refrigerant containers 65 below the roof and adjacent one of said walls, said wall having load supporting posts disposed adjacent the interior of the car, the

adjacent ends of each pair of containers being secured to the upper end of one of said posts, others of said posts being secured to said containers intermediate the ends thereof so that said containers form an upper chord of said wall.

4. In a refrigerator car having spaced apart side walls and a roof, a row of refrigerant containers below the roof and adjacent one of said walls, said wall having load supporting posts disposed adjacent the interior of the car, the upper ends of said posts being secured to said containers so that said containers form an upper chord of said wall, said containers having longitudinally extending frame members which extend beyond the ends thereof and are substantially in contact with members of adjacent containers.

5. In a refrigerator car having spaced apart side walls and a roof, a row of refrigerant containers below the roof and adjacent one of said walls, said wall having load supporting posts disposed adjacent the interior of the car, the upper ends of said posts being secured to said containers so that said containers form an upper chord of said wall, said containers having portions which extend beyond the ends thereof and are substantially in contact with portions of adjacent containers.

6. In a refrigerator car having spaced apart side walls and a roof, a row of refrigerant containers below the roof and adjacent one of said walls, said wall having load supporting posts disposed adjacent the interior of the car, the upper ends of said posts being secured to said containers so that said containers form an upper chord of said wall, said containers having longitudinally extending frame members which extend beyond the ends thereof and are substantially in contact with members of adjacent containers, the ends of adjacent containers being spaced apart for air flow therebetween.

7. In a refrigerator car having spaced apart side walls and a roof, a row of refrigerant containers below the roof and adjacent one of said

walls, said wall having load supporting posts disposed adjacent the interior of the car, the upper ends of said posts being secured to said containers so that said containers form an upper chord of said wall, some of said posts having portions disposed between the ends of adjacent containers and substantially in contact therewith.

8. In a refrigerator car having a lading compartment and a sill associated with the lower part of the car, the combination of spaced apart posts upstanding from said sill, lining carried by said posts to form a wall of said lading compartment, and refrigerating means above the lading compartment comprising an inherently rigid refrigerant container secured directly to the upper parts of said posts and arranged to form by itself a structural connection between said posts.

9. In a refrigerator car having a roof, a longitudinally extending row of refrigerant containers arranged below said roof, said containers having end walls disposed in a plurality of substantially parallel planes extending transversely of the car, the adjacent end walls of each pair of containers being spaced apart to provide a space for air circulation in contact with the containers, and means disposed at least partially in said space and arranged to cooperate with said last mentioned end walls to transmit a longitudinal thrust from one to another of said containers.

10. In a refrigerator car having a roof and a wall including substantially vertical posts, a longitudinally extending row of refrigerant containers arranged below said roof, said containers having end walls disposed in a plurality of substantially parallel planes extending transversely of the car, the adjacent end walls of each pair of containers being spaced apart to provide a space for air circulation in contact with the containers, and means carried by said posts disposed at least partially in said space and arranged to cooperate with said last mentioned end walls to transmit a longitudinal thrust from one to another of said containers.

CHARLES D. BONSALL.
